attorney.

UNITED STATES PATENT OFFICE

2,078,028

FLASHLIGHT

Paul Schneider, Berlin-Friedenau, Germany, assignor to Batterien-u. Elemente-Fabrik System Zeiler A.-G., Berlin, Germany, a company of Germany

Original application September 16, 1933, Serial No. 689,756. Divided and this application March 21, 1935, Serial No. 12,274. In Germany September 19, 1932

2 Claims. (CL 240—10.66)

My invention relates to battery hand lamps or flashlights, and more particularly to flashlights with a casing which comprises an upper and a lower portion, both of insulating material and connected for relative rotation and axial shifting, and a reflector in the upper portion. The lower portion receives a battery. At its lower end, it is closed by a solid or annular bottom plate which is integral with the casing. Its upper end is open.

5 It is an object of my invention to provide improved focussing means for a flashlight of this type.

To this end, I provide a transverse partition which is screwed upon the upper end of the lower casing portion, mount a bulb on the partition and provide means on the partition for shifting the casing portions axially with respect to each other upon relative rotation of the portions.

In the drawing

20 Fig. 1 is a partly sectional elevation of a preferred form of embodiment according to the invention.

Fig. 2 is an elevation thereof, viewed from the right in Fig. 1, and

25 Fig. 3 is a perspective illustration of the partition.

Referring now to the drawing, the flashlight comprises a lower portion 1 for the reception of a battery 3, and an upper portion 2 which is mounted on the lower portion for rotation and axial shifting, and knurled at 11. The lower portion is closed at the bottom by a bottom plate 14 which is integral with the lower portion 1. A spring 7 supports the battery 3 and is in turn supported by the plate 14. 4 is a switch at one side of the lower portion, for connecting the lamp bulb 9 to the battery 3 through any suitable conducting means, not shown. A reflector 8 is held in the upper portion 2 by a flange at its upper end, a transparent plate 11, and a knurled cap nut 13 which engages in a thread on the upper portion 2.

The lower end of the reflector 8 is tubular and surrounds, with some clearance, a socket 10 in which the bulb 9 is held. The lower end of the bulb contacts with the inner electrode of battery 3. The socket 10 is formed at the centre of a partition 51, Fig. 1, which includes two cylinders placed end on end. The lower cylinder is a threaded sleeve 70, and the upper cylinder 181 has cam slots 185, 186, and 187, and three spring tongues 182, 183, and 184 intermediate the slots. Three pins on the upper portion 2, one of which is shown at 188, engage in the respective cam

slots. There is no difficulty in making the cam slots in the sheet metal of cylinder 181, and in inserting the pins 188 in the insulating material of the upper portion 2. The tongues 182, 183, and 184 perform the function of springy arms 5 in holding the upper and the lower portion in position after the lamp has been focussed. The lamp socket 10 is in cylinder 181.

For focussing the lamp, the upper portion 2 is turned on the lower portion 1 and this turning movement is transformed into an axial shifting movement by the cam slots 185, 186 and 187. When the upper portion is released, it remains in the position to which it has been moved, as the tongues 182, 183, and 184 react against the inner side of the upper portion 2 and hold it in position on the lower portion 1. When the lower portion 1 is moved out of the upper portion, until the pins in the upper portion 2 are retained by the corresponding ends of their cam slots 185, 186 and 187, and is then rotated further, it becomes unscrewed from the sleeve 70 of partition 51 and the battery 3 can be removed from the upper end of the lower portion 1.

20 This case is a divisional application of applicant's original application, Serial No. 689,756, filed September 16, 1933.

25 I claim:

1. In a flashlight, a divided casing comprising 30 an upper portion of insulating material, a pin on said upper portion, a reflector in said upper portion, a lower portion, also of insulating material, a bottom plate at the lower end of said lower portion made integral therewith, said lower 35 portion being adapted to be rotated and shifted axially with respect to said upper portion, a threaded transverse partition, a thread at the upper end of said lower portion for holding said partition on the lower portion, a lamp bulb on 40 said partition, a tongue on said partition which is so arranged as to bear against the inner side of said upper portion by resilient reaction, and a member also on said partition, with a cam slot for said pin to engage in, for shifting axially 45 said portions with respect to each other upon relative rotation of said portions.

2. In a flashlight, a divided casing comprising 50 an upper portion of insulating material, pins on said upper portion, a reflector in said upper portion, a lower portion, also of insulating material, a bottom plate at the lower end of said lower portion made integral therewith, said lower portion being adapted to be rotated and shifted axially with respect to said upper portion, a trans- 55

verse partition including two hollow cylinders placed end on end, a thread on one of said cylinders, a thread at the upper end of said lower portion for holding the cylinder on the lower portion, a lamp bulb on said partition, the other cylinder having a cam slot for each of the pins

on said upper portion to engage in, and tongues arranged on said other cylinder so as to bear against the inner side of said upper portion by resilient reaction.

PAUL SCHNEIDER.
